UNITED STATES PATENT OFFICE.

CHARLES J. WHEALTON, OF NEAR MORRISON, VIRGINIA.

ANCHOR.

SPECIFICATION forming part of Letters Patent No. 430,793, dated June 24, 1890.

Application filed February 27, 1890. Serial No. 341,925. (No model.)

To all whom it may concern:

Be it known that I, CHARLES J. WHEALTON, a citizen of the United States, residing near Morrison, in the county of Warwick and State 5 of Virginia, have invented a new and useful Improvement in Anchors, of which the following is a specification.

My invention is an improvement in anchors; and my said invention consists in certain de- 10 tails of construction of the same, as and for the purposes as will be hereinafter more fully described, and form the subject-matter of the annexed claim.

Referring to the accompanying drawings, 15 forming a part hereof, for a better understanding of the details of construction of my invention, Figure 1 is a view in perspective of an anchor constructed according to my invention, and Fig. 2 is a view in sectional elevation of the same. Fig. 3 is a view in front elevation.

My anchor is composed of a straight shank A, to the top end of which is the usual stock B, and two separate crowns C and D, which 20 crowns are preferably triangular in shape and are formed at their extremities into diamond-shaped flukes c and d. The forward crown D, with its flukes d, is smaller than the rear crown C, and both crowns are secured in 25 line with each other to the shank A by pivot-pins a and a', and these crowns have a limited play in slots s s', formed in the shank A.

The flukes of the crowns C and D being triangular or diamond-shaped, as shown in 30 Fig. 3, the fouling of the chain or cable upon said flukes is prevented. To the outer end of the shank A, beyond the stock B, is swiveled a shackle-bar E, to the outer end of which bar is attached the cable or chain F, and this 35 bar E is one-half the length of the stock B, so that the end thereof will be even with the outer end of the stock, as shown in dotted lines in Fig. 1, so that fouling of said chain

or cable around the stock B is prevented, as 40 when the vessel is swinging around the cable or chain will clear the ends of the stock. Each of the crowns being, as before stated, pivotedly secured to the shank A, the strain 45 exerted upon the shank by the cable or chain will cause the lower half of the crowns to as- 50 sume a position nearly at a right angle with the shank A, so that the flukes will be carried deeper into the ground than they would were the crowns rigidly secured to the shank, as is 55 usually the case.

The crowns being both arranged in line 55 with each other and in the same direction relatively to the shank, and not at different angles relatively to each other, the flukes will not interfere with the vessel's rail, as 60 would be the case were the forward small crown at a different angle or at right angles with the position of the rear crown.

Having thus described my invention, I 65 claim—

An anchor composed of the straight shank A, having the stock B, secured at one end and formed with slots s s', triangular-shaped crown C, having diamond-shaped flukes c, pivotedly secured in the slot s at the lower 70 end of the shank A, triangular-shaped crown D of smaller size than the crown C, with dia- 75 mond-shaped flukes d, pivotedly secured in slot s' near the stock, and shackle-bar D, carrying the cable or chain at its outer end and connected by swivel to the shank A and one-half the length of the stock, as described and shown, for the purposes specified.

In testimony that I claim the foregoing as my own I have hereto affixed my signature in 80 presence of two witnesses.

CHARLES J. WHEALTON.
